Hiram Johnson

UNITED STATES PATENT OFFICE.

FRANK CRAWFORD, SR., OF NEW BRUNSWICK, NEW JERSEY, ASSIGNOR TO CRAWFORD MANUFACTURING COMPANY, OF NEW BRUNSWICK, NEW JERSEY, A CORPORATION OF NEW JERSEY.

TRIP ARM FOR STOP MOTIONS.

Application filed February 13, 1925. Serial No. 8,971.

The object of this invention is to provide means for counterbalancing the trip arm, or drop wire, of a stop motion of a knitting machine, or to increase or diminish the effective weight of the trip arm, as desired.

In the accompanying drawings:

Fig. 1 is a perspective view of my improved trip arm for stop motions;

Fig. 2 is a side view, showing the trip arm in connection with thread guides for stop motions;

Fig. 3 is an end view;

Fig. 4 is an enlarged sectional view on the line 4—4, Fig. 2;

Fig. 5 is a perspective view illustrating a modification;

Fig. 6 is a transverse sectional view on the line 6—6, Fig. 7;

Fig. 7 is a longitudinal sectional view of the modification shown in Fig. 5;

Fig. 8 is a side view of another modification; and

Fig. 9 is an end view of the modification shown in Fig. 8.

Referring to the drawings, an arm 1 projects from the main portion of a stop motion of a knitting machine. In a casing 2 of this arm is a spindle 3, which has a bent end 4 that is arranged to engage trip mechanism (not shown) when a thread breaks. Mounted on this spindle is an arm 5, which is formed by twisting the end of the arm and securing it on the spindle, as shown in Fig. 4. The arm 5 is bent, as shown in Fig. 2. Secured to the arm is a plate 6 that has an open center 7, which forms a ring. Thread guides 8 are so located in respect to this ring that the thread α passes in front of the ring, as shown in Fig. 3, and holds the arm in position so it will not trip the stop motion.

Secured to the spindle 3 is a head 9, which is formed with an opening 10 for a weight 11. This weight has a screw 12 that projects therefrom, and which extends through a slot 13 in the head 9. On this screw is a knurled nut 14. On turning the nut, the weight can be clamped to the head in any position desired relative to the centre of rotation of the spindle 3 to increase the effective weight of the arm or to decrease the weight, as desired, consequently increasing or decreasing respectively the pressure of the ring 6 against the thread α .

In the present instance, the head 9 is made

in two parts and the base portion 15 is notched at each side to receive the tongue 16 of a U-shaped portion 17, in which the slot 13 is formed. The parts are secured together by solder, or other suitable means. Other means of forming the head may be employed without departing from the essential features of the invention.

In Figs. 5, 6 and 7, a modification is illustrated, in which a weight 11^a is adapted to guides in a head 9^a. A light spring 18 is attached to one end of the weight and is coiled around a disk 19 to which it is attached at 20. The disk 19 has a stem 12^a on which is a squared portion to receive an adjusting disk 23. This disk is preferably graduated, as shown. On turning the disk 23, the spring is coiled or uncoiled to adjust the position of the weight 11^a. A knurled nut 14^a is mounted on the threaded portion of the stem to secure the disk 23 in the position in which it is adjusted. The upper end of the weight has a fork 21, which engages the arm 5^a to which the plate 6^a is secured. The head 9^a is mounted on a spindle 3^a of the type illustrated in Fig. 1.

In Figs. 8 and 9 is shown a modification, in which a head 9^b is in the form of a disk, which is mounted on a spindle 3^b. The arm 5^b is secured to the head and to the spindle 85 and carries the plate 6^b.

On a screw stem 22, projecting from the head 9^b, are two weights 11^b and 11^c, which can be adjusted on the stem to any position desired, and held by turning the screw stem, 90 which locks them rigidly to the head 9^b.

By the arrangement hereinbefore described, it will be seen that by providing a counterbalance for the trip arm, it can be made of comparatively heavy and substantial material, and the counterbalance weights can be adjusted to accommodate threads of different weights.

I claim:

1. The combination in a stop motion, of a supporting arm; a spindle rotatably mounted on said arm; a trip arm secured to the spindle, and having an enlarged opening adjacent its outer end; thread guides co-operative with said enlarged opening for receiving a thread adapted to hold the trip arm in a raised position; a head on the spindle having an opening extending transversely across the axis of said spindle; a sliding weight mounted in the said transversely

- extending opening in said head and adapted to be adjusted to any one of an infinite number of positions wherein the center of gravity of said weight is either coincident with 5 or adjacent either side of the centre of rotation of said spindle for increasing or decreasing the effective weight of the arm; and means for securing the weight in the position to which it is adjusted.
- 10 2. The combination in a stop motion of a pivoted trip arm; a weight mounted for movement in a plane extending transversely of the pivotal center of said trip arm, to a position wherein the center of gravity 15 of said weight is coincident with the said pivotal center of said trip arm, or to a position at either side of said pivotal center in said transversely extending plane.
3. The combination in a stop motion of a 20 rotatable spindle; a trip arm secured to said spindle; a weight adjustably mounted on said spindle and adapted to be moved in a plane extending transversely of the center of rotation of said spindle to a position 25 wherein the center of gravity of said weight
- is coincident with the said center of rotation of said spindle or to a position at either side thereof in said transversely extending plane.
4. The combination in a stop motion of 20 a spindle; a trip arm secured to said spindle and engaging a thread; a head on said spindle having an opening extending transversely across the axis of said spindle; a weight slidably mounted for longitudinal 35 movement in said opening and adapted to be moved to any one of a number of different positions within said opening, wherein the center of gravity of said weight is coincident with the center of rotation of said 40 spindle or located at either side thereof; and means for securing the weight in the position to which it has been adjusted for increasing or diminishing the pressure exerted by the trip arm on the thread or the 45 weight of said trip arm may be counterbalanced or overbalanced around the said axis of said spindle.

FRANK CRAWFORD, Sr.
